UNITED STATES PATENT OFFICE.

HENRY J. ENGEL, OF NEW YORK, N. Y.

SAFETY-RAZOR-BLADE HOLDER.

Application filed April 2, 1926. Serial No. 99,352.

This invention relates to improvements in safety razor blade holders, and has for its primary object, the provision of a means for safely and securely holding safety razor blades of the most popular makes so that they may be used for ripping seams, trimming paper, cutting furs and for other similar purposes, without subjecting the user to injury.

10 Another object of the invention resides in a safety razor blade holder which permits of the quick insertion and removal of an old safety razor blade, and when the blade is in position within the holder, a portion of the same is exposed for cutting purposes, but which portion may be covered or concealed when the holder is not in use by a suitable guard which is slidably mounted thereon.

With these and other objects in view, the 20 invention resides in certain novel construction and combination and arrangement of parts, the essential features of which are hereinafter fully described, are particularly pointed out in the appended claims, and are 25 illustrated in the accompanying drawing, in which:—

Figure 1 is a side elevation of the holder element per se.

Figure 2 is an end view of the same.

30 Figure 3 is a vertical transverse sectional view on the line 3—3 of Figure 1.

Figure 4 is a similar view on the line 4—4 of Figure 1.

35 Figure 5 is an elevational view of the sliding element.

Figure 6 is a vertical transverse sectional view on the line 6—6 of Figure 5.

Figure 7 is a similar view on the line 7—7 of Figure 5.

40 Figure 8 is an elevational view of the protecting guard.

Figure 9 is an end view of the protecting guard.

45 Figure 10 is an elevational view looking at the side of the guard opposite to that shown in Figure 8.

Figure 11 is a view of the holder element showing the manner of placing a blade of the Gillette type therein.

50 Figure 12 is a view similar to Figure 11 but showing the manner of inserting a blade of the single cutting edge type.

Figure 13 is a side elevational view of the holder with a blade mounted therein and the

guard member in a position to expose the 55 cutting edge of the blade.

Figure 14 is a vertical transverse sectional view on the line 14—14 of Figure 13.

Figure 15 is a detail perspective view of the holder element.

It will be appreciated that safety razor blades after becoming dull for comfortable shaving are still extremely sharp and for this reason they are utilized by tailors, seamstresses, housewives and furriers in their different occupations. These blades in their bare form are very dangerous, not only while using the blade for cutting purposes but also while they are lying around the table or baskets, due to the thin shape and extremely 65 sharp edges. I appreciate that various holders have heretofore been placed on the market for receiving razor blades, but they expose the full length of the blade, making their use dangerous due to the exposed end near the 70 handle where the fingers are adapted to rest and if they are provided with a protecting clip which necessitates its removal during use, the clip may easily become lost or misplaced. My invention is designed to overcome all of 75 these objections and the construction of which will now be described.

Referring more particularly to the drawings, the reference character A designates the main holder element which is constructed of 80 a single piece of material so formed as to provide a flat head 1 and a handle 2. An elongated slot 3 is provided in the flat head 1 and is adapted to receive one side of the top of a single edge blade being clearly shown 85 at B in Figure 12 of the drawing. The outer end wall of the slot 3 is provided with a recess 4 for accommodating a part to be presently described. At the joinder of the head 1 with the handle 2, the material is pressed 90 out to provide a stop 5 for limiting the inward movement of a double edge blade C such as shown in Figure 11 of the drawing. An elongated slit 6 is provided in the head 1 below the slot 3 and is adapted to slidably support a guard upon the head as will presently 95 be explained. The lower edge of the head 1 is cut-away or notched as at 7 to expose approximately one-half of the cutting edge of the blade.

100 Slidably mounted upon the head 1 is a slide element 8 which is provided with a longitudinally disposed cavity 9, correspond-

ing in shape to the slot 3, with the exception that the recess extends to the inner end of the slide for receiving the opposite side of the top of the single edge blade B. The lower end of the slide element is cut-away or notched as at 7 for alignment with the cut-away 7 in the head 1. The side edges together with the outer edge of the slide element are bent upon themselves as at 10, 11 and 12 to provide channels for receiving the corresponding edges of the head 1, the channels 10 and 11 serve to slidably support the element upon the head, while the front end 12 serves as a stop for limiting the insertion 15 of the element upon the head. The front end of the slide element is provided with an extending tongue 13 having an inwardly extending nose 14 which is adapted to snap into the recess 4 provided in the head 1 for holding the sliding element in a locked position upon the holder element. The sliding element is adapted to be constructed of very light metal to permit the bending of the side and end edges and to allow for the formation 20 of the cavity 9, which edges and cavity serve to strengthen the slide element.

The reference numeral 15 designates a protecting guard which is constructed from a light springy metal and is relatively U-shaped in cross section as shown in Figure 9 of the drawing. One of the sides of the guard 15 is flat for engagement with the outer side of the sliding element, while the opposite side of the guard is provided with an inwardly extending rib 17, which fits into a slit 6 for slidably mounting the guard upon the head 1. The wall of the guard which is provided with the rib 17 has one of its ends namely, 19, notched as at 16 to allow the guard to be moved to the extreme front end 30 of the slide element 8 and against the bent over edge 12. When it is desired to change the blades, it is not necessary to remove the guard 15 as there is sufficient clearance to remove or insert the blades when only the slide element is removed, thus any possibility of the guard becoming lost or misplaced is eliminated.

For the purpose of removing a blade for the insertion of a new one, the slide element is readily removed by holding the handle 2 with the left hand, passing the finger tips of the right hand on the underside of the part 1 and the thumb on top of the slide element, 50 after which a forward twist will spring the nose 14 out of the recess 4. By holding the guard with the thumb and index finger in place and pulling outward upon the sliding element 8 with the right hand, the blade can 55 easily be taken out either for reversing the blade to expose the other part of the cutting

edge or replacing the same by a new blade. When the new blade has been inserted the sliding element 8 may be replaced and pushed back until the nose 14 again snaps into the recess 4. It will be seen with reference to Figure 13 that when the device is adapted for use, the guard 15 may be moved backward to expose the cutting edge of the blade, but when not in use, the guard may be pushed forward to cover the exposed edge and eliminate any danger of injury by accidental cutting.

While I have described what I deem to be the most desirable embodiment of my invention, it is obvious that many of the details 75 may be varied without in any way departing from the spirit of my invention, and I therefore do not limit myself to the exact details of construction herein set forth nor to anything less than the whole of my invention 80 limited only by the appended claims.

What is claimed as new is:—

1. A safety razor blade holder comprising a member having a handle portion and a flat head at one end thereof, said head having an elongated slot therein, a portion of the lower edge of said head being cut-away, and an element slidable over said head and having an elongated cavity therein for co-action with said elongated slot for accommodating the head of a blade and for clamping the razor blade therebetween, said element having a notch therein to register with the cut-away portion in said head for exposing a portion of the cutting edge of said blade.

2. A blade holder comprising a member formed to provide a handle portion and a flat head at one end thereof, said head having an elongated slot therein, a slide element movable on said head and having a cavity for co-action with said elongated slot and adapted for clamping a safety razor blade therebetween, and co-acting means on said head and slidable element for locking the latter against movement.

3. A safety razor blade holder comprising a member formed of a single piece of material to provide a flat head and a handle portion, said head being notched along one of its edges, a longitudinal slit provided in said head, an element slidably mounted upon said head and having a notched portion for alignment with the notch portion in said head, a guard of relatively U-shape in cross section, and a rib extending inwardly from one of the walls of said guard for reception in said slit for slidably mounting said guard upon said head.

In testimony whereof I have affixed my signature.

HENRY J. ENGEL.
